BRASSIERE

Jack J. Lo Cascio, Bayonne, N. J., assignor to Even-Pul Foundations, Inc., New York, N. Y., a corporation of New York

Application January 6, 1956, Serial No. 39,640

Term of patent 14 years

(Cl. D20—4)

Figure 1 is a front perspective view of a brassiere, showing my new design; and

Figure 2 is a fragmentary front elevational view thereof on an enlarged scale.

The dominant features of my design reside in the portions shown by full lines. The sides and back of the brassiere are conventionally plain.

I claim:

The ornamental design for a brassiere, as shown and described.
